CLAIM

The ornamental design for a personal property securement device, as shown and described.

DESCRIPTION

FIG. 1 is a perspective view of a personal property securement device showing my new design.

FIG. 2 is a left side perspective view thereof.

FIG. 3 is a right side perspective view thereof; and,

FIG. 4 is a front right perspective view thereof.

The broken lines, which define the bounds of the claimed design form no part thereof. The raised broken line elements and a flexible shackle are for illustrative purpose only and form no part of the claimed design.
